Nov. 24, 2006 (JP) 2006-032218

The ornamental design for a portion of a scanner for a magnetic resonance tomography diagnosis apparatus, as shown and described.

(51) **LOC (8) Cl.** **24-01**

DESCRIPTION

(52) **U.S. Cl.** **D24/158**

FIG. 1 is a front, top and left side perspective view of a portion of a scanner for a magnetic resonance tomography diagnosis apparatus, showing my new design;

(58) **Field of Classification Search** D24/158-161; 378/4, 19-21, 23, 25, 27, 146; 324/309, 324/318, 319

FIG. 2 is a front elevational view thereof;

See application file for complete search history.

FIG. 3 is a rear elevational view thereof;

(56) **References Cited**

FIG. 4 is a top plan view thereof;
